UNITED STATES PATENT OFFICE.

JOHN VAN DER ELST, OF NEWARK, NEW JERSEY.

DESIGN FOR A CLOTHES-PIN.

SPECIFICATION forming part of Design No. 20,412, dated December 16, 1890.

Application filed October 31, 1890. Serial No. 369,981. Term of patent 3½ years.

To all whom it may concern:

Be it known that I, JOHN VAN DER ELST, a citizen of the United States, residing at Newark, in the county of Essex and State of New Jersey, have invented and produced a new and original Design for Clothes-Pins; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front elevation of the newly designed clothes-pin; and Fig. 2 is a section of the same, taken on line *x*.

The leading feature of the design consists in the round shape in cross-section of the prongs in connection with the peculiar tortuous shape of the same in front elevation

shown in the drawings and herein described.

In the drawing *a* is the clothes-pin. *b b* are the united prongs thereof, which are round in cross-section, as indicated in Fig. 2, and on their outer sides are convex, as at *c c*, concave, as at *d d*, then again convex, as at *e e*, and again concave, as at *f f*, the pin being ring-shaped at one end, as at *g*, and at the opposite end the extremities of the prongs flaring outwardly, as shown.

What I claim is—

The design for a clothes-pin herein shown and described.

In testimony that I claim the foregoing I have hereunto set my hand this 30th day of October, 1890.

JOHN VAN DER ELST.
